UNITED STATES PATENT OFFICE.

FREDERICK B. BLANCHARD, OF LEWISTON, MINNESOTA.

SACK-HOLDER.

SPECIFICATION forming part of Letters Patent No. 668,483, dated February 19, 1901.

Application filed April 21, 1900. serial No. 13,752. (No model.)

To all whom it may concern.

Be it known that I, FREDERICK B. BLANCHARD, of Lewiston, in the county of Winona and State of Minnesota, have invented a new and useful Improvement in Sack-Holders, of which the following is a specification.

My invention is an improvement in sack-holders, and has for an object to provide an improved construction of holder which will 10 adjust itself automatically to the length of the sack, will permit the sack to be entirely filled, thus avoiding refilling, will not injure the sack, will hold a sack which has no hem, requires but little space, and will greatly facilitate the filling of bags.

The invention consists in certain novel constructions and combinations of parts, as will be hereinafter described, and pointed out in the claims.

20 In the drawings, Figure 1 is a perspective view of my invention as in use. Fig. 2 is a detail perspective view of the sliding carrier for the bag-holding plates. Fig. 3 is a horizontal section of the holder, and Fig. 4 is a 25 detail view illustrating the movable support for the bag-holding plate.

In carrying out my invention I employ a suitable support or main frame, which is shown as a plate or board A, provided with 30 eyes A', through which may be passed screws or bolts for holding the board to a wall or other suitable support. The frame A has suitable guides B, on which slide vertically the carrier C for the plate-holding arms.

35 The carrier C has a main plate C', provided with portions C², looped over the guides B, and with forwardly-projecting bars D, which are provided near their outer ends with openings for the bolts E and F, which secure the 40 shanks G and H of the fixed and pivoted holders G' and H' for the mouth - holding plates G² and H².

The holders for the plates G² and H² are provided near their outer ends with depending portions g² and h², to which the plates G² and H² are fixed at their inner ends, the outer ends of the said plates being free and such plates being curved inwardly or returned toward their free ends, as shown.

50 The fixed holder G' is held from turning on its bolt E by fitting the free end of said holder

G' in a socket I in the main plate of the vertically-movable carrier, while the holder H' is movable pivotally on its bolt F and is actuated by a spring K, which operates the said 55 holder H' in such manner as to expand or spread the plate carried thereby. The spring K is shown as a coil-spring connected at one end to the shank of the holder H' and having at its other end a loop fitting on the shank of 60 the fixed holder G', thus anchoring the spring at such end, so it will properly operate the pivoted holder H', as desired.

In the operation of the invention the depending portions g² and h² permit the mouth 65 of the bag to extend up above the inner ends of the plates G² and H² secured to the holders G' and H', and the outer ends of the plates being also fitted within the mouth of the bag the said plates will lie entirely within such 70 mouth of the bag and when freed will operate to bind tightly within the bag in such manner as to securely hold the same. In this operation the form of the mouth - holding plates G² and H² in connection with the 75 spring K for actuating the pivotal holder for one of the plates renders the device capable of fitting any size of bag within a considerable range, as will be readily understood.

The carrier is spring-supported, being carried by a spring L, secured to the frame A above the carrier, and connected at its lower end with the carrier, so the latter may yield vertically to adapt it to any height of sack.

Manifestly the device may be adjusted up 85 or down to suit the height of the sack, its plates will adapt readily to any size of sack, and the sacks can be readily applied to the holder, properly filled, and readily removed.

By preference the plates G² and H² are provided on their outer sides with pins or spurs M, which enter the bag and aid in holding the same to the plates.

Having thus described my invention, what I claim, and desire to secure by Letters Patent, is—

1. In a sack-holder, the combination of the carrier C having bars D and a socket I, the plates, the holders for said plates, the bolts securing said holders to the bars D, one of 100 said holders engaging in the socket I and the other holder being pivoted as described, and

the spring for actuating the pivoted holder substantially as set forth.

- 5 2. A sack-holder comprising a base-plate or frame having guides, a carrier movable vertically on said guides and having forwardly-projecting bars, a spring supporting said carrier, curved plates free at their outer ends, supports to which the inner ends of said plates are secured, said supports being connected with the bars of the carrier and having depending portions to which the plates are secured, and a spring for actuating one of said supports, substantially as set forth.
- 10 3. A sack-holder comprising a base-plate

adapted to be suspended from a suitable support; the vertical guide-bars arranged upon the face of the base-plate and spaced apart from said plate; the carrier having a base-board fitting between the guide-bars and base-plate, and having loops fitting on the guide-bars; a spring connecting the carrier with the base-plate; and the holder on said carrier, substantially as set forth.

FREDERICK B. BLANCHARD.
